UNITED STATES PATENT OFFICE.

JOSEPH W. GOSLING, OF SCHENECTADY, NEW YORK, ASSIGNOR TO GENERAL ELECTRIC COMPANY, A CORPORATION OF NEW YORK.

DESIGN FOR AN ELECTRIC-LIGHTING FIXTURE.

60,452.

Specification for Design.

Patented Feb. 21, 1922.

Application filed February 12, 1921. Serial No. 444,617. Term of patent 14 years.

To all whom it may concern:

Be it known that I, JOSEPH W. GOSLING, citizen of the United States, residing at Schenectady, in the county of Schenectady, State of New York, have invented a new, original, and ornamental Design for an Electric-Lighting Fixture, of which the following in a specification, reference being had to the accompanying drawing, forming a part thereof.

The accompanying drawing is a perspective view of my ornamental electric lighting fixture, the radial wave formations on the lower edge thereof being reflectors.

What I claim is:

An ornamental design for an electric lighting fixture as shown and described.

In witness whereof, I have hereunto set my hand this 11th day of February, 1921.

JOSEPH W. GOSLING.
